PUTTEE

Ralph A. Le Fevre, Rochester, N. Y.

Application November 17, 1937, Serial No. 175,040

3 Claims. (Cl. 36—2)

The object of this invention is to provide a puttee that is made preferably of leather and will cover the upper part of the shoe and the leg up to and including the calf.

5 Another object of the invention is to provide a puttee that will shed the water and will be weatherproof.

Another object of the invention is to provide a puttee that is made extra wide and can be wrapped around the leg with three turns, and will provide ample support for the various parts of the leg.

10 Another object of the invention is to provide a puttee, the upper portion of which is composed of two pieces of leather sprung together and connected by a long seam.

Another object of the invention is to make the upper part of the puttee so that it will naturally conform to the upper part of the leg.

15 Another object of the invention is to provide the lower part of the puttee with a gaiter that will cover the front and sides of the shoe.

Another object of the invention is to provide the lower part of the puttee with a strap that engages under the arch of the shoe and anchors the lower part of the puttee in correct position for starting the wrapping. This makes it possible to put the puttee at once over the heel of the shoe after the strap has been once adjusted.

20 This also makes it possible to take the puttee off with the strap left in the adjusted position and makes it possible thereafter to start putting the puttee on around the heel by first passing the strap under the heel until it engages under the arch of the shoe and then proceeding to wrap the puttee around the leg.

25 These and other objects of the invention will be illustrated in the drawing, described in the specification, and pointed out in the claims at the end thereof.

In the drawing:

Figure 1 is a plan view of the puttee complete. Figure 2 is a side elevation of the right leg and foot with the puttee wrapped thereon, the leg being viewed from the outside.

30 Figure 3 is a side elevation of the right leg and foot with the puttee wrapped thereon, the leg being viewed from the inside.

Figure 4 is a sectional view through the puttee on the line 4x—4x of Figure 1, showing how it is sprung.

35 Figures 5 and 6 are detail views of the patterns or blanks from which the gaiter of the puttee is made.

40 Figure 7 is a detail view of the pattern or blank

that is wrapped around the leg from the ankle up.

Figures 8 and 9 indicate the patterns or blanks of the upper parts of the puttee that is wrapped around the calf of the leg and includes the belt by which the puttee is closed around the upper part of the calf of the leg.

45 In the drawing like reference numerals indicate like parts.

The puttee which constitutes my invention comprises several pieces of material, leather being preferably the material used. These pieces are described as follows:

In the drawing reference numeral 1 indicates a portion of the puttee that is wrapped around the leg from the ankle up. This piece conforms 15 practically to the pattern shown in Figure 7. 2 indicates one of the pieces in the upper part of the puttee that is wrapped around the calf of the leg, and 3 indicates the other piece of the upper part of the puttee that is also wrapped 20 around the calf of the leg. The parts 2 and 3 are joined together by a long seam 4 that is spaced nearly equally from the outer edges of the parts 2 and 3 and joins the intermediate part of the seam 5, by which the parts 2 and 3 are joined 25 to the part 1. The meeting edges of the parts 2 and 3 are not straight lines but are curved, and the joining of the parts together on these curved lines will cause the parts to be sprung with relation to each other forming a trough or barrel-shaped section such as is shown in Figure 4, which when wrapped around the calf of the leg 30 will naturally conform thereto.

Intermediate of the part 3 is fastened a buckle 6. Extending therefrom is a strap 7, which has 35 a series of holes therein, which passes through an eye 8 and is doubled back therefrom to engage the buckle 6.

It will be understood that this puttee can be used on any kind of shoes, and for this purpose 40 it includes a gaiter portion made of the parts 9 and 10, which are joined together by a seam 11. The seam 11 lies on top of the lacing of the shoe, if it is a laced shoe, and on the corresponding part of any other type of shoe.

45 A strap 12a is provided which goes under the arch of the shoe and engages with the buckle 13 by which the gaiter portion of the puttee is held securely in place on the shoe. The part 10 of the gaiter portion is joined with the part 1 by the seam 12, and at the top of the seams 11 and 12 the seam is cut away and left open for about an inch or more, as is indicated at 13a and 14. This enables the top of the gaiter to loosely conform to the front and back of the 50 55

leg at that part where the gaiter comes in contact.

On the part 1, at 15, 15 are provided the female parts or socket of the snaps which engage the male or stud parts of the snaps 16, 16 on the part 9 of the gaiter, and hold the parts closely in contact when in place. On the part 1 is also provided the female part or socket 17 which engages the male part or stud 18 of the snap 10 by which the puttee is fastened in place, as is shown in the intermediate part of Figure 3.

It will also be understood that when the socket 17 is closed on the stud 18 the puttee is positively locked in placed correctly on the leg and the 15 socket and stud acts as a gauge for wrapping the puttee both above and below it. When the socket and stud are closed, the upper part of the puttee will on its own account conform to the upper part of the leg.

20 The part 9 of the so-called gaiter portion of the puttee covers the outside of the shoe as shown in Figure 2, and the part 10 covers the inside of the shoe as shown in Figure 3, and the strap 12a goes under the arch as shown in Figure 3, and 25 engages with the buckle 13 as shown in Figure 2. A recess 14 is provided that will engage at the back of the foot or tendon over the heel, and the recess 13a will engage on the front of the foot above the instep, lying centrally thereon. These 30 recesses are provided to prevent chafing.

It will also be understood that the section marked 9a and 10a can work up and down on the gaiter 9 and 10 without chafing the tendon or the leg.

35 The long part 1 wraps around the lower part of the leg beginning at the ankle and the upper parts 2 and 3 wrap around the calf and are fastened thereon by the strap 7 and buckle 6.

In Figures 1, 2 and 3 I have shown a puttee 40 that is adapted to fit and to be worn on the right foot and leg. By reversing the shape of the parts, keeping them symmetrical with the parts shown, the puttee will be adapted for use on the left foot and leg.

45 It will also be understood that this puttee will naturally shed water, and is much wider than puttees ordinarily used and this makes it possible to wrap it round the foot and leg with but three turns.

50 In the sample puttee from which the drawing was made the total length of the part 1 between the corners 20 and 21 is twenty-three and a half inches, and the other dimensions of the part 1 and of the other parts are in proportion.

55 The parts of the puttee are made wide so that they will cover the leg and calf with a few number

of turns, in this instance three turns above the gaiter being sufficient. In this and other respects this puttee is an improvement on that shown in my prior application Serial No. 71,191, filed March 27, 1936.

5

I claim:

1. A puttee for covering the lower leg, comprising a lower portion constituting a gaiter and adapted to cover the upper portion of the foot, said gaiter portion being made of two pieces joined together by a seam, said seam being adapted to be located over the center line of the heel of the shoe, said pieces being sprung upwardly along the lower portion of said seam, a band attached to one end of the gaiter and having a curved outline, said band being made of three pieces, the upper part of the band being made of two pieces joined together by a long seam, the lower part of the band being made of one piece, the upper end of the lower part 20 and the lower end of the upper part being joined together by a short seam extending directly across the band, said long seam extending from the middle of the short seam up to near the end of the puttee and being nearly evenly spaced 25 from the upper and lower edges thereof, the two pieces of the upper part being sprung together along the long seam, said band being adapted to be wrapped around the leg up to and including the calf of the leg, means for fastening the upper end of the puttee in place on the calf of the leg.

2. The combination in a puttee of a gaiter adapted to cover the upper portion of a shoe, a band attached to said gaiter to wrap around the 35 leg, the band and the gaiter being cut away at the top to form a recess so that the gaiter and puttee will loosely conform to the front of the leg.

3. A puttee for covering the lower leg, comprising a lower portion constituting a gaiter and adapted to cover the upper portion of the foot, said gaiter portion being made of two pieces joined together by a seam, said seam being adapted to be located over the center line of the 45 heel of the shoe, said pieces being sprung upwardly along the lower portion of said seam, a band attached to one end of the gaiter and having a curved outline, a stud near the lower end of said band, a socket higher up on said band 50 near the intermediate part thereof, said socket being adapted to engage the stud whereby the intermediate part of the puttee is locked in place correctly on the leg.
